MICHEL DASSONVILLE, OF PARIS, FRANCE

DEVICE FOR CURLING THREADS MADE OF CELLULOSIC MATERIAL AT THEIR ISSUE
FROM SPINNING MACHINES

Application filed June 8, 1929, Serial No. 369,451, and in France October 30, 1928.

A process is known for the manufacture of a cellulosic product having the appearance of wool, which consists in subjecting cellulose threads issuing from a coagulation bath and before their molecular stability is complete, to a reduction or suppression of the tension which must be exerted on them for pulling them out of the bath, and in compelling them to retract on themselves in order to give them a waved conformation having a certain analogy with that of natural wool.

In order to obtain the wavings or curlings, use is made of a scraper constituted by a movable metal blade pressed by the action of a spring against the winding up drum placed at the outlet of the coagulation bath. This scraper detaches in fact from the said winding up drum, at a suitable place and in a continuous manner, the material in the form of a group of threads, by thus imparting to it a change of direction and a crimping or curling which gives it the desired appearance of natural wool.

The face of the scraper against which the material abuts, must form with the surface of the drum, on the side where this material arrives, an angle which may vary from 45° to 150°, but which practically remains between 100° and 120°. Below 45°, the material would tend to accumulate in the angle formed by the drum and the scraper and the operation would be defective. At 45°, the curling produced is extremely close; it is less and less close in proportion as the angle increases; it becomes scarcely apparent when the angle reaches 150°; above 150° no curling whatever is produced and the material is simply detached from the surface of the drum.

The most suitable angle depends on the consistency of the material, on its degree of adherence on the drum and on the degree of curling desired.

The systems of detaching blades used up to now theoretically allow to effect the curling operation, but they present in practice numerous inconveniences, particularly arising from the fact that the inevitable wear of the rubbing end of the blade is not sufficiently rigorously regular for allowing uniform op-

eration and regular detaching of the artificial wool.

Besides it sometimes happens that the detached and waved material follows the detaching blades by sticking on the same during a certain time, instead of constantly falling as soon as it is detached; the pressing by a spring, of the blade against the drum is also rendered very variable and very irregular owing to the action of the steam or of acids on this member which is, owing to its resiliency and to its relatively large surface, very sensitive to the action of the various external agents.

The invention which will be described has for its object an improved system of scraper which avoids the above mentioned inconveniences.

Owing to the improvements which will be described:

(1) The scraper, in fact, always automatically presses against the drum in a rational and regular manner without having to effect its adjustment.

(2) A blunt edge, even slightly blunt, can be nearly instantaneously replaced by another one without any difficulty.

Owing to its shape and to its special assemblage the scraper never stops the wool in its advance during the operation.

The accompanying drawings illustrate, by way of example, a form of construction of the device in accordance with the present invention.

Fig. 1 shows in elevation the scraper pressed against the winding up drum.

Fig. 2 is a plan view corresponding to Fig. 1,

Fig. 3 is a sectional view, on an enlarged scale, of a detail of construction.

Fig. 4 illustrates the entire machine and shows the position of the blade of the scraper on this machine.

Fig. 5 is a detail view, on an enlarged scale, showing the shape and arrangement of the scraper.

The scraper device illustrated is composed of a metal scraper 1, the shape of which is so devised as to prevent artificial wool from sticking on the same after curling.

This scraper has a cross section in the shape of an equilateral triangle and its arrangement relatively to the winding up drum is such that the angle α formed by the front face of the scraper, and the tangent to the drum at the point of contact of the scraping edge is preferably between 100 and 120°, so that the cellulosic material drawn up by the drum and abutting against the front face of the scraper 10 is detached, turned back and curled by this scraper in the required manner.

This scraper is supported by a blade-carrying fork 2 on which it is secured by two small clamping screws 13 which allow to very simply and very rapidly remove and replace the scraper, provided, however, the abutment 9, to be mentioned later on, is previously manipulated.

The fork 2 terminates in a socket which fits 20 on the end of a rod 4 and is connected thereto through the medium of a pin 12 (Fig. 3).

The pin is forcibly fitted in the rod 4 and is rigid with the same, but the socket of the fork 2, the hole of which has a very oval shape, 25 on the contrary freely moves on the said pin in the transverse direction, this allowing the fork 2 to rotate to a certain extent about the rod 4. This rotation of the fork limited to a few millimeters in each direction, is of the 30 highest importance, considering it allows of pressing the scraper always very exactly on the winding up drum 3.

The rod 4 carrying the fork 2 slides in a support 5 and is secured thereto by a locking 35 screw 14, this allowing the exact adjustment of the point of application of the scraper on the winding up drum 3.

The support 5 is provided, on the other hand, with two trunnions rotating in bearings 6 secured on the sole member 7 so that if the said support which drives the whole structure is caused to rotate, the resilient application of the scraper on the winding up drum can be obtained; it results therefrom that the 40 cellulosic material has no possibility of partly passing between the scraper and the drum and of sticking to the latter although it is of very small thickness and in a very soft condition and this whatever may be the irregularities of the surface of the drum and its 45 eventual eccentricity.

This resilient application of the scraper on the drum is obtained by means of a rider 10, urged by a counter-weight 11 which allows 50 to adjust the pressure of the scraper on the winding up drum.

The entire structure rests through the medium of the sole member 7 on a bearing 8 secured to the cheeks 15 of the frame.

The abutment 9 already mentioned allows, by being screwed home, of lifting the rod 4 and of holding the scraper-carrying fork 55 spaced from the winding up drum during the replacement and turning over the scraper.

From the above description, the following advantages are obviously obtained:

(1) The scraper, owing to its triangular cross section with perfectly defined angles, 60 allows the artificial wool in proportion as it is detached from the winding up drum, to move away by always preserving its waviness and without ever sticking to the scraper.

(2) The scraper is removable and can be 65 easily replaced, when it is necessary to sharpen it or to change it for any reason.

(3) The shape of the scraper allows moreover to successively utilize its three edges by 70 simply displacing it on its support.

(4) The scraper-carrying fork being movable and capable of rocking about an axis situated in the plane passing in the mean circle of the drum, allows the cutting edge of the 75 scraper to fit exactly on the periphery of the winding up drum.

(5) The resilient application of the scraper on the winding up drum: being effected by a counter-weight controlled by a rider, is not influenced by the action of external agents.

Claims:

1. In a machine for spinning cellulosic products and having a rotary drum serving to pull the threads when they issue from the coagulation bath, the combination of a lever 85 rocking about an axis parallel to that of the said drum, this lever having an end in the shape of a trunnion, a socket freely mounted on this end of the lever so as to be capable of rocking according to a small angle about its axis, this socket being terminated by a forked portion, a scraper of prismatic shape mounted in the said forked portion and adapted to bear by one of its edges against the surface of the said winding up drum, and a counter-weight 90 adjustable on the said lever, adapted to press the said scraper against the drum.

2. In a machine for spinning cellulosic products and having a rotary drum serving to pull the threads when they issue from the 100 coagulation bath, the combination of a lever rocking about an axis parallel to that of the said drum: a forked piece mounted on this lever so as to be capable of rocking about an axis orthogonal to that of the drum, the 105 branches of this forked piece having triangular recesses, a scraper in the shape of a triangular prism, the ends of which are fitted in the said recesses, and adapted to bear by one of its edges against the surface of the drum, 110 and a counter-weight adjustable on the lever, adapted to press the said scraper against the drum.

3. In a machine for spinning cellulosic products and having a rotary drum serving 115 to pull the threads when they issue from the coagulation bath, the combination of a lever rocking about an axis parallel to that of the said drum, a scraper pivotally mounted on this lever about an axis at right angle to the 120

125

axis of the drum, a counterweight on the said lever adapted to press the said scraper against the drum, and a screw adapted to push the said lever back against the action of the said counterweight.

5 In testimony whereof I have hereunto affixed my signature.
